CLAIM

We claim the ornamental design for a gauge housing, as shown and described.

DESCRIPTION

FIG. 1 is a perspective view of our design for a gauge housing; FIG. 2 is a front view of the design for a gauge housing shown in FIG. 1;

FIG. 3 is a right side view of the design for a gauge housing shown in FIG. 1;

FIG. 4 is a left side view of the design for a gauge housing shown in FIG. 1;

FIG. 5 is a top view of the design for a gauge housing shown in FIG. 1;

FIG. 6 is a bottom view of the design for a gauge housing shown in FIG. 1;

FIG. 7 is a rear view of the design for a gauge housing shown in FIG. 1; and,

FIG. 8 is a front view of the design for a gauge housing shown in FIG. 1 illustrating an exemplary gauge within the housing design.

The broken lines shown in FIGS. 2 and 8 are in no way intended to form part of the claimed design and are for illustrative purposes only.
